UNITED STATES PATENT OFFICE

LLEWELLYN J. W. JONES, OF TACOMA, WASHINGTON, ASSIGNOR TO JAMES F. O'BRIEN,
OF SEATTLE, WASHINGTON

EXPLOSIVE

No Drawing.

Application filed March 17, 1927. Serial No. 176,291.

My invention relates to explosives whose characteristic ingredients are chlorates or perchlorates of an alkaline metal, or of ammonium.

5 I am aware that patents have been issued covering the use of liquid oily dinitrotoluene with chlorates or perchlorates of alkaline metals, or of ammonium, together with carbonaceous substances, and with or without 10 nitrates of the alkaline metals, or of ammonium, and restrainers such as silico-aluminous substances and carbonates of the alkaline earths, but it has been found that such powders are not constant in quality 15 with the lapse of time.

I particularly find that during the winter months, when the temperature falls to the freezing point of water and the atmosphere is surcharged with moisture during the rainy 20 periods, that the explosive qualities of the powder are partly, and sometimes wholly, lost.

I have discovered that the reason for this condition is that the commercial oily dinitrotoluene is not of sufficiently definite a composition and that it has a solidifying point varying, in different samples, from 30° C. to 25 66° C., and that when it solidifies it does so in a crystalline mass.

30 In the practical manufacture of these chlorate powders it is necessary to heat the so-called oily dinitrotoluene to remove it from the steel drums in which it is shipped, and to keep it in liquid condition for mixing the other powder ingredients therewith. 35 No difficulties are experienced until after the powder is made and packed into cartridges.

After being packed into cartridges, however, the strength of the powder rapidly falls 40 during the first two or three days, it then remains fairly constant during the summer months but, when the cold weather sets in, it loses its strength still more, occasionally 45 even failing to explode. The reason for this is that the powder loses its plasticity and fails to transmit, with sufficient force and rapidity, the heat and shock of the detonating cap.

50 I have discovered that these difficulties can

be overcome by the substitution in the above outlined ingredients, of a part, or the whole, of the dinitrotoluene by an appropriate proportion of mononitrotoluene, specifically the orthoisomer which is liquid to as low a 55 temperature as -10° C. and remains liquid at all higher temperatures up to its boiling point, 218° C. The advantage of using the orthonitrotoluene is that its readily dissolves the dinitrotoluenes and, if used in sufficient quantity, will prevent their crystallization and maintain the powder in its plastic condition indefinitely.

At the present time the cartridges, after being filled, must be crimped by hand as it is important that the powder be loosely packed on account of the swelling and hardening that results from its crystallization. By the use of the orthonitrotoluene, however, this crystallization is prevented and therefore it is possible to substitute an automatic crimping machine for this manual labor, thereby attaining two important results (a) a reduction in the cost, and (b) 60 avoiding the troublesome skin inflammation (dermatitis) which constant contact with the powder produces on the hands of some of the workers.

I find that it is possible to substitute the orthonitrotoluene for the dinitrotoluene 65 completely, but for other reasons, particularly its poisonous effect on the workers, I prefer to use as small a quantity as possible. I find that a mixture of one-third ortho- to two-thirds di-nitrotoluene gives us 70 very satisfactory results but it is to be understood that the proportions can be varied to suit the conditions of climate and temperature as needed.

In order to attain the best results in the 75 waterproofing of the powder I mix the orthonitrotoluene first with the dinitrotoluene (which has been liquefied or melted in order to remove it from the drums) in the desired proportions and I then pour this 80 warm liquid mixture over the thoroughly dry warm salts and other dry ingredients.

The carbonaceous substance which I prefer to use is sawdust, but any of many others 85 may be used with substantially the same re- 90

sults, such as charcoal, flour, starch, etc. As restrainers I prefer to use either silico-aluminous substances, such as brickdust, powdered clay, or sand, or carbonates of the alkaline earths, particularly calcium carbonate, such as limestone, and such restrainer being in a finely powdered condition.

My improved explosive therefore comprises chlorates or perchlorates of alkaline metals, specifically sodium or potassium, or of ammonium, with or without nitrates of alkaline metals, specifically sodium or potassium, or of ammonium, carbonaceous substances, with or without silico-aluminous substances or alkaline earth carbonates, and liquid orthonitrotoluene, with or without liquefied or melted dinitrotoluene, the said dry substances being thoroughly mixed with the said liquid, whereby each grain thereof is coated with the said liquid.

The exact proportions of which the various kinds of powders are composed will vary within rather wide limits, depending on the character of the work required of them, their cost, and the circumstances under which they are to operate, for instance the following would be typical powders:—

Rock powder #1		Parts	95
Sodium chlorate	78		
Dinitrotoluene	10		
Orthonitrotoluene	5		
35 Sawdust	7		

Rock powder #2		Parts	100
Sodium chlorate	73		
Sodium nitrate	7		
46 Sawdust	5		
Dinitrotoluene	10		
Orthonitrotoluene	5		

Stumping powder #1		Parts	110
45 Sodium chlorate	40		
Sodium nitrate	38		
Sawdust	7		
Dinitrotoluene	10		
50 Orthonitrotoluene	5		

Stumping powder #2		Parts	115
Sodium chlorate	33		
Sodium nitrate	40		
55 Sawdust	9		
Dinitrotoluene	12		
Orthonitrotoluene	6		

Having therefore described my invention what I claim is:—

1. An explosive composed of chlorates of alkaline metals; finely divided carbonaceous substances; and the ortho isomer alone of mononitrotoluene.
2. An explosive consisting of chlorates of alkaline metals; finely divided carbona-

ceous substances; and a mixture of orthonitrotoluene with crystalline dinitrotoluene liquefied by heat.

3. An explosive consisting of chlorates of alkaline metals; alkaline nitrates; finely divided carbonaceous substances; and a mixture of orthonitrotoluene with crystalline dinitrotoluene liquefied by heat.

4. An explosive consisting of sodium chlorate; finely divided carbonaceous substances; and a mixture of liquid orthonitrotoluene with crystalline dinitrotoluene liquefied by heat.

5. An explosive consisting of sodium chlorate; sodium nitrate; finely divided carbonaceous substances; and liquid orthonitrotoluene mixed with crystalline dinitrotoluene liquefied by heat.

6. An explosive consisting of sodium chlorate, 70 to 80 parts; orthonitrotoluene, 5 to 10 parts; melted dinitrotoluene, 10 to 13 parts; and sawdust 5 to 10 parts.

7. An explosive consisting of sodium chlorate, 5 to 50 parts; sodium nitrate, 5 to 50 parts; orthonitrotoluene, 5 to 15 parts; dinitrotoluene, 5 to 15 parts; and saw-dust, 5 to 15 parts.
